AUTOMOBILE-MOUNTED CAMPING UNIT

Howard J. Leichner, 1510 N. Neil St., Champaign, Ill.

Filed Nov. 4, 1963, Ser. No. 77,256

Term of patent 14 years

(Cl. D14—3)

Fig. 1.

Fig. 2.

FIG. 1 is a perspective view of the automobile-mounted camping unit embodying my new design, taken from the rear thereof.

FIG. 2 is a perspective view similar to FIG. 1 but taken from the front of the unit.

The dominant features of my design reside in the portions shown in full lines. The automobile shown in broken lines in FIG. 1 and fragmentarily in FIG. 2 is included for illustrative purposes only. The side opposite that appearing in the drawings is a mirror image of that shown.

I claim:

The ornamental design for an automobile mounted camping unit, as shown and described.
